Patented June 9, 1959

185,455

HAIR CURLING DEVICE

Ruth McGrath, Chicago, Ill.

Application December 19, 1957, Serial No. 48,960

Term of patent 14 years

(Cl. D86—10)

FIG. 1

FIG. 2

FIG. 3

FIG. 4

FIG. 5

FIG. 6

Fig. 1 is a side elevational view illustrating one of three like sides equally spaced around the periphery of my hair curling device;

Fig. 2 is a side elevational view illustrating one of three like sides equally spaced and viewed oppositely from the side shown in Fig. 1;

Fig. 3 is an end sectional view of my hair curling device taken substantially on line 3-3 of Fig. 2 and looking in the direction of the arrows;

Fig. 4 is an end elevational view illustrating one of two like ends of the device shown in Figs. 1 and 2;

Fig. 5 is an end sectional view taken substantially at the position indicated by a line 5-5 in Fig. 2 and looking in the direction of the arrows; and

Fig. 6 is a side elevational view showing the device substantially from a position indicated by a line 6-6 and accompanying arrows in Fig. 5.

I claim:

The ornamental design for a hair curling device, substantially as shown.
